ELECTRIC FLATIRON

Gilbert Waage, Chicago, Ill., assignor to Edward
P. Schreyer, Milwaukee, Wis.

Application February 11, 1939, Serial No. 255,839

7 Claims. (Cl. 177—311)

This invention relates to electrically heated flatirons and, in its most complete and preferred form, to a type of such flatirons designed to afford various degrees of heat such as low, medium, and high, and in the heating system of which is incorporated a normally closed thermostatic switch adapted to automatically open the circuit when a maximum degree of heat has been reached in the flatiron, and automatically close when the heat has subsided below such maximum.

Heretofore, as far as I am aware, a single thermostatic switch has been employed to limit the several degrees of heat obtainable in the iron, such switch being adjustable to open at low, medium or high, as desired. Such a device is poor and unsatisfactory, because experience has shown that the switch, with repeated and frequent adjustments, through wear and for other causes becomes unreliable and short lived, 20 requiring frequent renewal.

One object of this invention has been to provide an improved electric heating system for flatirons which will overcome the above noted objection and afford greater reliability, uniformity and longevity of the automatic thermostatic control.

Another object has been to provide a visual heat condition signal means for indicating when the iron is delivering a low, medium or high heat, or no heat at all. Such a signal device is valuable to prevent the use of the iron at high heat on articles that will stand only medium or low heat without scorching, and the use of the iron at medium heat on articles that will stand only low heat without scorching.

Another object has been to provide an improved manually operated switch mechanism preferably located in the handle of the flatiron, by means of which the user may, by a slight movement of thumb or a finger, selectively switch the current between "low," "medium," "hot" and "off."

Still other objects and advantages of the invention will be apparent to persons skilled in the art from the subjoined description of a practical and approved embodiment thereof shown in the accompanying drawings, in which—

Fig. 1 is a vertical longitudinal section through 50 the flatiron.

Fig. 2 is a vertical transverse section taken on the line 2—2 of Fig. 1.

Fig. 3 is a side elevation of a rotatable separa-

control the "off" condition and the low, medium, and high heat circuits.

Fig. 4 is a view of the opposite side of the separator disc.

Fig. 5 is a developed section of the separator disc on the circular line 5—5 of Fig. 3, the side appearing in Fig. 3 being uppermost.

Fig. 6 is a view mainly in longitudinal section of the manual switch assembly that is preferably located in the handle and is operated by the separator disc, showing all of the switch contacts separated corresponding to the "off" position.

Figs. 7, 8 and 9 are views similar to Fig. 6 but mainly in elevation, showing positions of the switch contacts corresponding to low, medium, and high heat respectively.

Fig. 10 is a diagram of the circuits and the manually operated and automatic thermostatic switches therein.

Describing first the manually operated switch assembly which is preferably located in the handle, as shown in Fig. 1, 11 and 12 designate a pair of longitudinally opposed U-shaped frame members that at their inner open ends straddle a pair of insulation blocks 13 and are secured to the latter by rivets 14 (Fig. 1). Clamped between the blocks 13 is a fixed conductor plate 15 carrying on opposite sides thereof at one end button contacts 16 and 17. Also attached to the outer sides of the blocks 13 by bolts 18 are a pair of flexible resilient conductor strips 19 and 20. Strip 19 carries a pair of button contacts 21 and 22 on opposite sides thereof lying opposite contact 16, and strip 20 carries a pair of button contacts 23 and 24 on opposite sides thereof lying opposite contact 17. As shown in Fig. 1, the sides of the frame members 11 and 12 are longitudinally slotted to allow the strips 19 and 20 to be disposed in the planes of the sides of the frame members. The bolts 18 also extend through a pair of short insulation blocks 25, securing the latter to the outer sides of the blocks 13, and to the blocks 25 are attached by bolts 26 a pair of conductor strips 27 and 28. Strip 27 carries a button contact 29 lying opposite contact 21, and strip 28 carries a button contact 30 lying opposite contact 23. Since the blocks 25 overlie the conductor strips 19 and 20, mica insulating strips 31 are interposed to prevent short circuits through the attaching bolts 26.

The several circuits controlled by the above described switch assembly are all normally open, as shown in Fig. 6, which corresponds to the "off" condition of the heater. The manually operated means for selectively closing the circuits which

give low, medium, and high heats follows in principle a somewhat similar means disclosed in my Patent No. 2,054,147, dated September 15, 1936. 32 designates as an entirety a rotatable separator disc that is journaled on a pivot pin 33 between the side walls of the frame member 11. In this disc is an arcuate slot 34 through which extends a fixed pin 35 to limit the turning movement to about 90 degrees. Through the disc are formed four parallel holes 36, 37, 38 and 39 (Fig. 5). Hole 36 is formed with relatively deep countersinks 36' at each end thereof. Hole 37 is formed with a relatively shallow countersink 37' at one end while its other end is flush with the other side of the disc. Hole 38 has a shallow 15 countersink 38' at one end, while its other end is flush with the other side of the disc. Hole 39 has shallow countersinks 39' at both ends. These holes have no significance beyond providing a convenient means for locating and centering the several countersinks or recesses, and ventilating and cooling the disc. The two conductor strips 19 and 20 extend beyond their button contacts to overlap the sides of the disc 32 and are provided on their inner sides with buttons 40 20 and 41 that, under the elasticity of the strips 19 and 20, are lightly pressed against the sides of the disc 32. These buttons 40 and 41 have no current conducting function, but lie opposite the semi-circular path of the holes 36, 37, 38 and 39, 25 and snap into the countersinks of said holes when the latter are moved into register with the buttons 40 and 41.

In the "off" position of the disc 32 shown in Figs. 1, 6 and 10, the buttons 40 and 41 are seated in the countersinks 39', and all of the circuit closing contacts are separated. In the low heat position of disc 32 shown in Fig. 7 button 41 lies in countersink 38', but button 40 lies against the side wall of disc 32 opposite the end of hole 36, 40 and this flexes strip 19 outwardly and closes a low heat circuit through contacts 21 and 29. In the medium heat position of disc 32 shown in Fig. 8, button 40 lies in countersink 37', but button 41 lies against the other side wall of disc 32 45 opposite the end of hole 37, and this flexes strip 20 outwardly and closes a medium heat circuit through contacts 23 and 36. In the high heat position of disc 32 shown in Fig. 9 both buttons 40 and 41 lie in the deep countersinks 36', and this closes both the low and medium heat circuits through buttons 22 and 16 on one side of conductor plate 15 and buttons 24 and 17 on the other side of said conductor plate. On the periphery of the disc 32 are position indicia such as 46 "Off," "Low," "Med" and "Hot," the uppermost indicating the thermal condition of the iron that will follow the setting of the indicator.

Describing now the electric circuits, and the heating elements, automatic thermostatic switches, and signal lights included therein, and referring to the diagrammatic view Fig. 10, A and B designate two power supply lines from the opposite poles of a source of electric current. Continuous with line A is a line 42 connected to which at 47 43 is the bi-metallic member 44 of a normally closed thermostatic switch designated as a whole by 45. From the switch 45 a line 46 extends to and through a heat condition signal light 47 which, as shown in Fig. 1, may consist of a high resistance glow wire interposed in the line 46. Thence the line 46 extends to a connection with the flexible strip 21. The return branch of this line from the manual switch is through the contacts 29 and 21, strip 19, line 48, to and through 50

a relatively short heating coil 49, and from the latter by lines 50 and 51 to the other supply circuit line B.

Connected to line 42 at 52 is a bi-metallic member 53 of a second thermostatic switch 54, from which a line 55 leads to and through a second heat condition signal light 47', and thence to the flexible conductor 28; the return being through the contacts 30 and 23, flexible conductor 20, and line 56 to a relatively long heating coil 51, and from the latter by return lines 58 and 51 to the other side B of the supply circuit line. Also connected to the line 42 at 59 is a bi-metallic member 60 of a third thermostatic switch 61, from which a line 62 leads through a third heat condition signal light 47'' and thence to and through the conductor plate 15, from which latter the return is by way of contacts 17 and 24, strip 20, line 56, heating element 51, and line 58 to line 51 on one side, and through contacts 16 and 22, conductor strip 19, line 48, heating element 49 and line 50 to line 51 on the other side. It will thus be seen that when contacts 17 and 24 and contacts 16 and 22 are both closed (as shown in Fig. 9) both of the low and medium heat circuits are connected in parallel to give the high heat or "hot" effect.

The manner in which this heating and signaling system is installed in the flatiron is illustrated in Figs. 1 and 2. 63 designates the shoe and 64 a flat weight superimposed on the shoe and fastened thereto by screws 65. Between the shoe and weight are the heating coils 49 and 57 wound on a mica form conventionally shown at 58 and insulated by upper and lower mica sheets 51 and 68. Since this specific form of electric heating element is old and known, the same is not herein illustrated in detail. Surmounting the shoe 63 and attached to the weight 64 by long screws 69 is a metal shell 70, through the top of which extends the lower horizontal limb of a metal handle support 71, to and between the upper ends of which is secured by screws 72 a hollow handle 73 which contains the manually operated switch assembly. To the underside of the top or dome of the shell 70 is centered and attached by the screws 69 and a screw 74, an insulation block 75 in the top of which are formed pockets 76, 77 and 78 for the glow wire lights 47, 47' and 47'', and these pockets are covered by green, amber and red glass hoods 79, 80 and 81 respectively that project slightly through openings in the top wall of the shell 70.

The light given off by the glow wires passes through holes 82 (Fig. 2) in the lower limb of the handle support 71 that register with the pockets, and thence through the colored hoods 76, 78 and 81, so that the differently colored lights are clearly visible to the user. Below the insulation block 75 is an insulation block 83 that forms a convenient support for the thermostatic switches, and in the rear portion of the hollow body is another insulation block 84 secured to the shell 70 by the threaded stems of two prongs A and B that, together with the surrounding sleeve 85 attached to the rear limb of the handle support, form a socket to receive a female plug on the electric supply line. The block 84 constitutes an intermediate support for the several circuit lines leading to the thermostatic switches and to and from the switch assembly in the handle.

In using the iron, the separator disc is turned to bring the "Low," "Med" or "Hot" designation uppermost, according to whether a low, me-

dium or high heat is desired, which causes the green, amber or red light to show. And since these lights are in separate branch circuits only one of which is closed at any time, only one light will show at a time. Of course, a short interval of time is required to bring the iron up to the particular heat indicated by the light selected, but if, during the ironing operation, the heat of the iron should rise slightly above the maximum of the heat selected, the thermostatic switch of the circuit in use will open the circuit, thus preventing danger of scorching. The chief value of the individual circuit lights and thermostatic switches, however, is to prevent danger of scorching when shifting from a higher to a lower heat. To illustrate, suppose the laundress has been using the high or medium heat and shifts the separator disc to bring on the next lower heat. At this time the thermostatic switch of the circuit giving the next lower heat is open, and will not close until the iron has cooled sufficiently to be at the maximum of the next lower heat. Hence, the laundress knows that the iron should not be used until the signal light of the next lower heat circuit is visible. Obviously, this result can be attained by a single heat condition signal, such as a light, in a single heating circuit, with automatic heat-energized means, such as a thermostatic switch, controlling the circuit.

Thus, when shifting either from a lower to a higher heat or from a higher to a lower heat, all danger of scorching is automatically obviated.

The details of structure and arrangement herein shown and described may be varied within the skill of the designer and maker of electric flatirons without departing from the invention, and hence I do not limit the invention to such details except to the extent clearly indicated in the claims.

I claim:

1. In an electric iron, electrically energized means for delivering a relatively high heat, an electric circuit for said means, electrically energized means for delivering a lower heat, an electric circuit for said last means, manual switch means for opening said high heat circuit and for preparing said lower heat circuit for operation, a thermostat for maintaining said lower heat circuit in open condition after said manual switch has been thus operated and for closing said lower heat circuit only when the temperature of the iron drops below a predetermined value substantially less than the temperature at the time of opening the high heat circuit, and an electrically operated signal in the circuit to said lower heat delivering means to indicate when the temperature of the iron has dropped below said predetermined value and when it is safe to use the iron on fabrics which would be scorched by a higher temperature.

2. In an electric iron, electrically energized means for delivering a relatively high heat, an electric circuit for said means, a visual electric signal in the circuit to said high heat delivering means, electrically energized means for delivering a lower heat, an electric circuit for said last means, manual switch means for opening said high heat circuit and for preparing said lower heat circuit for operation, a thermostat for maintaining said lower heat circuit in open condition after said manual switch has been thus operated and for closing said lower heat circuit only when the temperature of the iron drops below

10 a predetermined value substantially less than the temperature at the time of opening the high heat circuit, and an electrically operated visual signal, of different appearance than the high heat signal, in the circuit to said lower heat delivering means to indicate when the temperature of the iron has dropped below said predetermined value and when it is safe to use the iron on fabrics which would be scorched by a higher temperature.

3. In an electric iron, electrically energized means for delivering a relatively high heat, an electric circuit for said means, a visual electric signal in the circuit to said high heat delivering means, a thermostat controlling said high heat circuit, electrically energized means for delivering a lower heat, an electric circuit for said last means, manual switch means for opening said high heat circuit and for preparing said lower heat circuit for operation, a thermostat for maintaining said lower heat circuit in open condition after said manual switch has been thus operated and for closing said lower heat circuit only when the temperature of the iron drops below a predetermined value substantially less than the temperature at the time of opening the high heat circuit, and an electrically operated visual signal, of different appearance than the high heat signal, in the circuit to said lower heat delivering means to indicate when the temperature of the iron has dropped below said predetermined value and when it is safe to use the iron on fabrics which would be scorched by a higher temperature.

35 4. In an electric iron, an electric heating element for delivering a relatively high heat, an electric circuit for said element, an electric heating element for delivering a lower heat, an electric circuit for said last heating element, manual switch means for opening the circuit to said high heat element and for preparing the circuit of said lower heat element for operation, a thermostat for maintaining said lower heat circuit in open condition after said manual switch has been thus operated and for closing said lower heat circuit only when the temperature of the iron drops below a predetermined value substantially less than the temperature at the time of opening the high heat circuit, and an electrically operated signal in the circuit to said lower heat delivering element to indicate when the temperature of the iron has dropped below said predetermined value and when it is safe to use the iron on fabrics which would be scorched by a higher temperature.

45 5. In an electric iron, an electric heating element for delivering a relatively high heat, an electric circuit for said element, a visual electric signal in the circuit to said high heat element, an electric heating element for delivering a lower heat, an electric circuit for said last heating element, manual switch means for opening the circuit to said high heat element and for preparing the circuit of said lower heat element for operation, a thermostat for maintaining said lower heat circuit in open condition after said manual switch has been thus operated and for closing said lower heat circuit only when the temperature of the iron drops below a predetermined value substantially less than the temperature at the time of opening the high heat circuit, and an electrically operated visual signal, of different appearance than the high heat signal, in the circuit to said lower heat delivering element to indicate when the temperature of the iron has

dropped below said predetermined value and when it is safe to use the iron on fabrics which would be scorched by a higher temperature.

6. In an electric iron, an electric heating element for delivering a relatively high heat, an electric circuit for said element, a visual electric signal in the circuit to said high heat element, a thermostat controlling said high heat circuit, an electric heating element for delivering a lower heat, an electric circuit for said last heating element, manual switch means for opening the circuit to said high heat element and for preparing the circuit of said lower heat element for operation, a thermostat for maintaining said lower heat circuit in open condition after said manual switch has been thus operated and for closing said lower heat circuit only when the temperature of the iron drops below a predetermined value substantially less than the temperature at the time of opening the high heat circuit, and an electrically operated visual signal, of different appearance than the high heat signal, in the circuit to said lower heat deliv-

ering element to indicate when the temperature of the iron has dropped below said predetermined value and when it is safe to use the iron on fabrics which would be scorched by a higher temperature.

7. In an electric iron, means including an electric heater adapted to heat the iron to a relatively high temperature or to a lower temperature, manually operated means for stopping said high temperature operation and for preparing for low temperature operation, means including a thermostatic element operable when the iron has cooled to a predetermined value below its temperature at the time high temperature operation was stopped for causing low temperature operation of said heating means to begin, and an electric signal in series with said thermostatic element indicating when it is safe to use the iron on fabrics which would be scorched by a temperature higher than the maximum allowed by said thermostatic element.

GILBERT WAAGE.
